UNITED STATES PATENT OFFICE

158,253

VANITY TRAY

Jack Gantz, Rye, N. Y.

Application May 27, 1949, Serial No. 2,910

Term of patent 14 years

(Cl. D86—10)

To all whom it may concern:

Be it known that I, Jack Gantz, a citizen of the United States and resident of the city of Rye, county of Westchester, and State of New York, have invented a new, original, and ornamental Design for Vanity Tray, of which the following is a specification, reference being had to the accompanying drawing, forming part thereof.

The figure is a perspective top view of a vanity tray, showing my design.

I claim:

The ornamental design for a vanity tray, substantially as shown.

JACK GANTZ.
